UNITED STATES PATENT OFFICE.

WILLIAM E. SHERWOOD, OF ONEIDA, NEW YORK, ASSIGNOR OF ONE-HALF
TO WILLIAM E. DOUGLAS, OF SAME PLACE.

THILL-COUPING.

SPECIFICATION forming part of Letters Patent No. 673,481, dated May 7, 1901.

Application filed November 24, 1900. Serial No. 37,574. (No model.)

To all whom it may concern:

Be it known that I, WILLIAM E. SHERWOOD, of Oneida, in the county of Madison, in the State of New York, have invented new and 5 useful Improvements in Thill-Couplings, of which the following, taken in connection with the accompanying drawings, is a full, clear, and exact description.

My invention relates to improvements in 10 thill-couplings; and the object is to provide a simple and efficient coupling that may be easily and quickly applied without removing a bolt and that will be suitable for connection with almost any draft-iron in use, including 15 those used on modern small-wheeled vehicles.

To this end my invention consists in the combination of a strap adapted to be secured to the shaft and provided with a rigid jaw, a 20 movable jaw below the rigid jaw turning on a pivot passing transversely through the strap, a lever hinged to a lug on the lower side of the said strap, and a spring connecting the 25 movable jaw with a pivot passing transversely through the said lever intermediate its length; and my invention consists in certain other combinations of parts hereinafter described, and specifically set forth in the claim.

In the drawings hereto annexed and forming 30 a part of this specification, Figure 1 is a sectional side elevation of my improved thill-coupling, showing the draft-eye or jaws closed. Fig. 2 is a side elevation of the same, showing the coupling removed from the draft-iron of the vehicle and with the draft-eye or 35 jaws open. Fig. 3 is a side elevation of the spring connections and shows how the spring is wrapped around the pivot in the movable jaw. Fig. 4 is a lower side plan view of the 40 device when the jaws are closed, and shows the jaws connected to a draw-iron integral with the clip-plate instead of the clip, and serves to illustrate that the coupling is adapted to be connected to various forms of draft-irons and is not limited to any particular 45 form.

Referring specifically to the drawings, A is 50 a portion of the axle, provided with the usual clip A' and clip-plate A'' below the axle. The clip shown in Fig. 1 has the common forwardly-extending ears a a, through which

passes the bolt or rivet B, enveloped between the ears by a rubber tube c or washer to prevent rattling. In Fig. 4 the ears are integral with the clip or tie plate and not with the clip, 55 as in Fig. 1. The form of draft-iron is quite immaterial, as any suitable and well-known draft-iron may be used with my invention.

C is the metallic strap adapted to be secured to the lower side and end portion of a 60 pole or thill D and is preferably provided with upwardly-projecting lips d d on opposite sides to hold the thill in place. The end of the strap C is provided with a fixed and integral semicircular jaw e on its end to bear upon 65 and partly envelop the rubber tube c. The lower jaw f has also a semicircular portion and is movable toward and from the upper jaw and is provided with ears lying on opposite sides and in recesses in the strap C just 70 forward of the fixed jaw, through which ears and part of strap between them passes a rivet or pivot f', on which the movable jaw swings. The two jaws form the draft-eye and when closed completely and closely envelop the rubber tube on the bolt. 75

Projecting downwardly from the lower side of the strap or thill-iron a considerable distance forward of the jaws is a lug g. To this lug is pivoted a bifurcated lever E, which is 80 preferably provided on its free end with a loop h for a safety-strap. The pivot i passes transversely through the bifurcated end of the lever and the lug, so that the lever swings toward and from the jaws. The said lever is 85 slightly curved and is connected with the movable jaw f by means of a spring F, having a substantially flat central portion and eyes at opposite ends for connection with the transverse pivots k and l, passing through the ears 90 n on the movable jaw and the lever, respectively. The end of the spring F between the ears n of the movable jaw f is also provided with a helical spiral s for the purpose of allowing greater flexibility and to insure against 95 the breaking of the eyes when the lever is operated. It also allows the central portion of the spring to be made straight, so as to lie close to the lower side of the strap C and between the strap and the lever when the jaws 100 are closed.

Fig. 1 shows a loop h' on the forward end

and integral with the clip-plate A" and a safety-strap connecting the loop h' with the loop h on the end of the lever E.

When the jaws are closed or when the parts 5 are in the position shown in Fig. 1, the movable jaw is securely held up and locked in that position and cannot be moved or opened until the lever E is thrown downward and forward, and considerable force must be applied to the lever to swing the same downward, owing to the arrangement of the connecting parts.

Having described my invention, what I claim as new, and desire to secure by Letters 15 Patent, is—

In a thill-coupling, the combination of a metallic strap secured to the shaft and pro-

vided with a rigid jaw, a movable jaw below the rigid jaw turning on a pivot passing through the said strap, a lever hinged to 20 the strap forward of the jaws, and a spring having eyes at opposite ends connecting the movable jaw with the lever intermediate its length, said spring having a substantially straight central portion and a helical end portion at the eye connected to the movable jaw, as and for the purpose described.

In testimony whereof I have hereunto signed my name.

WILLIAM E. SHERWOOD. [L. S.]
